CENTRIFUGAL SPINNING, TWISTING, AND
ANALOGOUS MACHINE

William Prince-Smith, Keighley, England

Application May 25, 1940, Serial No. 337,297
In Great Britain May 15, 1939

3 Claims. (Cl. 57—34)

This invention relates to spinning, twisting, and analogous machines, and in particular to machines, for the centrifugal spinning, twisting, or the like, of yarns, threads and similar fibrous materials, wherein each yarn is traversed vertically by a reciprocating guide within a revolving yarn holder upon the inner surface of which the yarn is laid centrifugally and from which yarn holder it is subsequently caused automatically to be wrapped on to a bobbin or like externally wound package inserted thereinto from below and provided with means to engage the yarn in order to initiate its transfer to the bobbin, the yarn delivery means being automatically stopped for that purpose and the yarn holder continuing to revolve.

The invention has for its principal object to provide a machine, for the centrifugal spinning, twisting or the like of yarns or threads, whereof the construction and operation secure a high rate of production without detriment to the yarns or threads however delicate their nature; another object being to reduce to a minimum the strains to which the yarns are subjected adjacent their delivery point in centrifugal spinning and like machines.

According to the invention, the means for guiding and the means for traversing the yarns in a centrifugal spinning, twisting or like machine of the kind specified, are so designed and cooperate that the delivery angle of the yarn to the yarn holders remains constant during the building of the yarn masses within the holders.

To this end, adjacent each yarn holder there is provided a stationary yarn guide in respect to which a traverse guide is reciprocable within the holder and is shaped so as to avoid, during its reciprocatory movement, the path of the yarn extending from the drawing rollers to the yarn guides.

In one constructional embodiment of the invention a centrifugal spinning, twisting or like machine may be provided with a series of individually driven yarn holders into each of which a stationary tubular yarn guide and a reciprocable tubular traverse guide project axially, and a series of bobbin supports may be located below said series of yarn holders to enable bobbins or like externally wound packages to be manipulated with respect thereto.

These individually driven yarn holders may be supported in overhead bearings carried by the machine frame which also supports the stationary yarn guides co-axially with said holders; and the reciprocable traverse guides, into which the

yarns are directed from the drawing rollers by said stationary yarn guides, may be non-rotatably disposed concentrically of the yarn guides in respect to which they may be moved collectively by means of a traverse rail and suitable traversing mechanism.

Each spinning or like unit may comprise an inverted cup-shaped yarn holder having a vertical tubular stem surrounded by a driving whorl and secured in ball bearings mounted in an overhead bracket carried by the machine frame below and forwardly of the drawing rollers, and held in a fixed bracket and projecting through said stem above the top of each holder there may be a guide tube having in its upper end a pot eye 15 constituting a stationary yarn guide.

Concentrically with and externally of said stationary guide tube, a second tube may be arranged slidably and may be provided with an eyelet at its lower extremity, said second tube or 20 traversing guide being non-rotatable and being slotted vertically to permit its passage past the bracket supporting the stationary yarn guide and also to avoid during its reciprocation contact with the yarn extending from the drawing rollers to 25 the stationary thread guide.

Each tubular traversing guide is supported by a bracket extending from a traverse rail carried by the usual pokers, and the connection between each guide and its bracket may be detachable.

This detachable connection may consist of a link articulated to a horizontal lug secured to the upper end of said tubular guide, which link may be provided with a depending peg to be received by an aperture in the supporting bracket. 35 Further, in order to enable each tubular traverse guide to be maintained in an elevated position when necessary or desirable, each guide may be formed with a notch at right angles to and at an appropriate height in the vertical slot therein. 40

The invention is illustrated by way of example in the accompanying drawings which show, in sectional elevation a portion of a machine frame and as much of a spindle unit and its associated parts as are necessary to the understanding of 45 the invention as applied to the known type of centrifugal spinning machine embodying inverted cup-shaped yarn holders.

Figure 1 shows the position of the parts at the completion of the spinning of a yarn mass within 50 a yarn holder, and Figure 2 the position of the parts just prior to the commencement of the re-winding operation. Figure 3 is a fragmentary plan view showing the connections to the means for traversing the yarn within the yarn holder, 55

Figure 4 is a fragmentary rear elevation of part of said yarn traversing means, and Figure 5 is an enlarged detail sectional view.

- 1 represents part of the main framework of 5 one side of the machine to which is secured a plurality of brackets 2 supporting a fixed horizontal continuous rail 3. 4 indicates one of the lower front rollers by which the yarn Y is delivered to the respective spindle units.
- 10 Secured at intervals along the rail 3 is a number of overhead brackets or cages such as 5, each carrying upper and lower ball bearings 6, 6, whereof the inner races are fast on the tubular stem or neck 7 of an inverted cup-shaped yarn holder 8 supported by the cage 5 and adapted to be driven through the medium of the usual or appropriate mechanism by means of a tape (not shown) passing around a whorl 9 fixed to the tubular stem or neck 7.
- 15 20 Located below and coaxially with each yarn holder 8 is a spindle 10 secured adjustably in a bracket 11 fixed to a continuous rockshaft 12 supported at intervals by rack pillars such as 13 mounted so as to be slidable vertically in guides 25 such as 14 fixed to a stationary continuous rail 15, the rack pillars 13 being actuated by pinions such as 16 keyed to an operating shaft 17 extending along the machine and deriving motion from known or appropriate mechanism not 30 shown.
- The upper end of each spindle 10 terminates in a bobbin peg 18 at the lower end of which is a flange 19 upon which a bobbin 20 rests.
- 21 is a bracket secured to the top of the cage 35 5 and projecting forwardly so as to maintain a guide tube 22 concentrically within the tubular neck 7 of the yarn holder 8; the lower extremity of said guide tube 22 terminating slightly above the top of the yarn holder 8, and the upper end 40 of said tube 22 being fitted with a pot-eye 23 constituting a stationary yarn guide.
- 24 is a traverse rail supported at intervals as usual by pokers such as 25 and adapted to be operated in the well understood manner by build- 45 er or traversing mechanism, and to this traverse rail 24 is secured adjacent to each spindle unit a forwardly projecting bracket 26 which supports a slidable tube 27 concentrically with and ex- ternally of said stationary guide tube 22.
